UNITED STATES PATENT OFFICE.

JAMES EDWARD DOWD, OF SALT LAKE CITY, UTAH.

TONSIL REMOVER.

Application filed September 25, 1925. Serial No. 58,579.

This invention relates to improvements in tonsil removers.

The present device relates generally to the form of the instruments now used for removing tonsils by what is known as the "Sluder" method.

The prime purpose of the invention is to provide an instrument or device of the above character which will enable tonsils to be removed with little or no bleeding.

A further object of the invention is that the instrument or device be provided with means whereby the tonsils removed, together with any material expressed from a tonsil during its removal, will be efficiently removed from the patient's throat.

It is also an object of the invention that the instrument or device be adapted to permit tonsils to be quickly removed and thereby enable a short anesthetic to be employed when removing tonsils.

It is also within the scope of the objects of the invention that the device or instrument be compact, easy to operate, and not subject to getting out of working order.

Other objects and objects relating to details of construction, combination and arrangement of parts will hereinafter appear in the detailed description to follow.

In carrying out my invention I provide a handle having an elongated frame or stock projecting therefrom which may be extended into a person's throat, said frame or stock having an opening in its free end adapted to accommodate a tonsil. The frame carries a crusher bar and a cutter bar, both capable of being operated by the thumb of the operator's hand grasping the handle of the device. The crusher bar serves the purpose of crushing the tissue holding a tonsil to its associated throat wall; the cutter bar serves to cut the crushed tissue. The crushing of the tissue prevents bleeding. I also provide a receptacle so arranged upon the end of the elongated frame or stock that a severed tonsil will drop therein together with any matter which may be expelled from a tonsil during the removal thereof.

The invention is illustrated by way of example in the accompanying drawings in which:—

Figure 1 is a perspective view of the device showing the crusher bar and cutter bar in normal or inoperative position.

Figure 2 is a vertical longitudinal sec-

tional view taken on line 2—2 of Figure 1.

Figure 3 is a schematic view illustrating the principle upon which my device operates in removing a tonsil.

Figure 4 is a view similar to Figure 2 but showing different positions for the tissue crusher bar and lever for operating the same.

Figure 5 is a perspective view of the crusher bar.

Figure 6 is a group view showing in perspective the elongated frame for carrying the crusher bar and cutter bar, together with means for mounting the lever which operates the crusher bar.

Figure 7 is a perspective group view showing the cutter bar with its removable blade, and the operating button therefor.

Figure 8 is a perspective view of the support for the tonsil receptacle or bag.

Referring to the drawings more particularly, 10 indicates generally a handle which may be of any desired shape. The handle has extending therefrom an elongated frame or stock 11 which terminates at its outer end in a head 12 having an opening 12' adapted for receiving a tonsil. The upper side of the frame or stock 11 is preferably flat as shown at 13. The head 12 has its forward end 14 rounded as shown and said end is provided with a slot 15. The inner side of the rounded portion 14 is rough as shown at 16. The head 12 is provided with a bead or enlargement about 90 its edge and the two side portions of the enlargement 17 each has its inner side formed with the longitudinally extending grooves 18 and 19, the grooves 19 being arranged above grooves 18.

Slidable upon the stock 11 is a cutter bar generally indicated by the reference character 20 which comprises a carrier member 21 and a blade 22. The stock 11 is provided with a longitudinally extending groove into which the member 21 is slidably fitted. The blade 22 is removably secured to the member 21 as shown. The member 22 has its forward end provided with an enlargement 23' which has a cutting edge 23' and said enlargement is adapted to slide in grooves 18 of the head 12.

Upon the cutter bar 20 there is movable a crusher bar 23, said bar being provided at its forward end with an enlargement 24 which has a curved forward end 25 corresponding to the curvature of the inner side

of portion 14 of head 12. The enlargement 24 of the crusher bar 23 is also provided with lugs 26 which are adapted to slide in grooves 19 of head 12.

5 The cutter bar 20 carries pins 28 and 29 which are movable in slots 30 and 31 respectively of the crusher bar 23.

The rear end of the cutter bar 20 has a depending lug 32 which is adapted to engage 10 the free end of a leaf spring 33 carried by handle 10. The last named end of cutter bar 20 has threaded therein a screw 34 which 15 turnably supports a button 35. The opening in the button through which the screw 34 extends is sufficiently enlarged adjacent the inner side of the button to accommodate a coil spring 36. The spring 36 permits limited movement of the button 35 toward the associated end of the cutter bar 20. The 20 button 35 carries a lug 38 and a spherical peripheral protrusion 39. The lug 38 is adapted to be brought to register with the associated end of the crusher bar 23 or with the lug 32 carried by the cutter bar 20. The 25 protrusion 39 serves to indicate the position of lug 38 on the button 35 and to provide means for quickly turning the button from one position to another.

The handle 10 is further provided with 30 two lugs 41 which occur at the inner end of the frame or stock 11. Each lug 41 is formed with an opening 42 adapted to journal the ends of a roller 43. The roller 43 is formed with teeth or ribs 44 which may be 35 brought into mesh with similar teeth or ribs 45 on the crusher bar 23. The roller 43 is further provided with an elongated lug 46 which is adapted to be brought into the recess 47 in crusher bar 23. Each end of the 40 roller 43 is provided with an extension 47' which is square in cross section and upon these extensions there is fitted the terminals of a U-shaped lever generally indicated by the reference character 48. One terminal of 45 the U-shaped lever member 48 is held upon its associated extension 47' of roller 43 by a set screw 50 and washer 50' while the other terminal is held in position by a screw 51 having a knurled head 52.

50 The bridge portion of the U-shaped lever member is provided with a thumb plate 53'. One of the lugs 41 of handle 10 may have the periphery of its opening 42 formed with a notch 54 to facilitate the positioning of 55 the roller 43; while the remaining lug 41 of said handle has formed therewith a lug or 60 detent 55 which is adapted to move in a depression 56 formed in the end of the associated terminal of the U-shaped lever member 48 and serve to limit the swinging movement of said lever.

65 The crusher bar also carries a pin 56 which is adapted to engage the roller 43 and limit rearward movement of said crusher bar. The pin 56 secures one end of a leaf

spring which extends between said pin and teeth 45. The spring normally engages beneath the roller 43 and maintains the crusher bar 23 upon the cutter bar 20 and serves as a tension spring to hold crusher bar in open position while instrument is being applied.

The handle 10 also carries a spring pressed ratchet lever 58 which is L-shaped and mounted as shown. This lever is provided with teeth 59 which may be brought to engage with a lip 60 formed upon the rear end of thumb plate 53'.

Now referring to Figure 8 there is shown a sack or bag holder generally indicated by the reference character 61, and comprising a frame 62 adapted to be fitted upon the lower side of head 12. The frame is formed with an extension 63 preferably bent as at 64 adjacent its inner end. Adjacent the outer end of extension 63 there is formed an opening 65. As shown in Figures 2 and 4 a set screw may be extended through opening 65 and the bag holder 61 secured to the stock 11. The bag holder extension 63 may be formed with tangs 66 which may be employed for further securing the same to the stock 11. As best illustrated in Figure 2 the upper end of a bag or sack 61 may be clamped between the frame 62 and the bottom side of head 12. The bag 68 may be of any size, shape and material desired.

In the use of the instrument heretofore described, the stock 11 is extended down the patient's throat and the tonsil to be removed brought into the opening 12' of head 12. The operator, of course, grasps the handle 10 with one hand, and after he has properly positioned the head 12 of stock 11, the button 35 having been previously arranged so that its lug 38 will register with the associated end of the crusher bar 23, he then with his thumb pushes forward upon the button 35 which will force the crusher and cutter bar forward. The crusher bar should be moved forward until the teeth of roller 43 engage teeth 45 on crusher bar 23. At this moment the operator may swing downward lever 48 and force the crusher bar 23 further forward. The lever 48 may be brought to a position for engagement with ratchet lever 58 and then locked against movement as illustrated to advantage in Figure 4.

Now referring to Figure 3, it will be observed the crusher bar 23 has been advanced to crush the tissue holding the tonsil to the throat wall. At this period the operator should rotate the button 35 to bring its lug 38 into register with the cutter bar lug 32 and then push forward upon button 35 whereby the cutter bar 20 will be forced forward and sever the crushed tissue holding the tonsil to the throat wall. The tonsil and all matter escaping therefrom will drop into the bag 61 and the instrument can now be withdrawn from the patient's throat, or

- if desired the remaining tonsil may be removed in the manner heretofore described. It will be noted the individual forward movement of cutter bar 20 will bring lug 32 into engagement with spring 33 and depress said spring. It is therefore apparent that immediately upon releasing the cutter bar the same will be retracted to its normal position with respect to crusher bar 23.
- 5 10 Also by releasing lever 48 and swinging the same upwardly the crusher bar and cutter bar are brought to their original or non-operative position, and the device is ready for proceeding with the removal of another tonsil.
- 15 It is to be here pointed out that the device can be easily operated, and from the description given it is apparent the same can be employed for removing tonsils in an exceedingly rapid manner. Also it will be observed from the structure of the device that the same can be easily dissembled if desired. The blade 22 can be removed without difficulty and likewise the bag 61.
- 20 25 While I have shown and described the preferred form of my invention I wish it to be understood that I am aware of the fact that the general structure, combination, and arrangement of parts might be changed by those skilled in the art without departing from the spirit of my invention as indicated by the appended claims.
- 30 35 What I claim is:
1. A tonsil remover, comprising a stock having an opening adjacent one end thereof for receiving a tonsil, tonsil severing means carried by the stock and adapted to sever a tonsil when disposed in said opening, and a bag carried by the stock having its mouth surrounding said opening and adapted to receive a tonsil when severed.
  2. A tonsil remover comprising a handle adapted to be grasped by a hand of an operator, a stock or frame extending from the handle having an opening at its free end adapted for receiving a tonsil, a tissue crusher bar longitudinally slidable in the stock and its forward end adapted to be brought between the tonsil and associated throat wall and crush the tonsil holding tissue against the forward wall of said receiving opening, means to permit the thumb of the operator's hand grasping the handle to be utilized for pushing forward the crusher bar a certain degree and properly position the forward end of the bar for crushing tonsil holding tissue, and lever means whereby forward tissue crushing movement of the bar may be obtained.
  3. A tonsil remover comprising a handle adapted to be grasped by a hand of an operator, a stock or frame extending from the handle having an opening at its free end adapted for receiving a tonsil, a tissue crusher bar longitudinally slidable in the stock and its forward end adapted to be brought between the tonsil and associated throat wall and crush the tonsil holding tissue against the forward wall of said receiving opening, means to permit the thumb of the operator's hand grasping the handle to be utilized for pushing forward the crusher bar a limited degree and properly position the forward end of the bar with relation to the tissue to be crushed, and lever means operable by the same thumb of the operator whereby forward tissue crushing movement of bar may be obtained.
4. A tonsil remover comprising a stock or elongated member having an opening in one end for receiving a tonsil, means for severing the tonsil, a bag carried by the stock and disposed to receive a tonsil when severed or detached, and means permitting easy detachment of bag from the stock.
5. In a device of the character described, a supporting frame or stock, a pair of parallel bars reciprocally supported by the frame, and a member supported at one end of one of the bars and capable of being manipulated so that the same may be employed for manually pressing either of said bars in a similar direction.
6. In a device of the character described, a supporting frame or stock, a pair of parallel bars reciprocally supported by the frame and a lug or knob supported upon the end of one of said members for axial movement and capable of being manipulated for manually pressing either of said bars in a similar direction.
7. In a device of the character described, a supporting frame or stock, a pair of parallel bars reciprocally supported by the frame, a knob rotatably supported upon one end of one of said bars, said knob being free for axial movement and adapted to normally be utilized for manually moving the last named bar in one direction, a lug or extension carried by the knob adapted to be brought into register with the associated end of the other bar and enable said knob to be utilized for manually moving said bar in the same direction.
8. In a device of the character described, a supporting frame or stock, a pair of parallel bars reciprocally supported by the frame, a knob rotatably supported upon one end of one of said bars, said knob being free for axial movement and adapted to normally be utilized for manually moving the last named bar in one direction, a lug or extension carried by the knob adapted to be brought into register with the associated end of the other bar and enable said knob to be utilized for manually moving said bar in the same direction, and means upon the knob to visually indicate when the lug upon the knob is in register with the last named bar.
9. In a device of the character described,

a crusher bar longitudinally movable, a segmental rack carried by said bar, a lever controlled pinion, said pinion being adapted to engage the rack and move the bar forwardly 5 a limited degree when said pinion is rotated in one direction by said lever, and means for locking the lever bar after the crusher bar has been given its full forward movement.

10 10. In a device of the character described, a crusher bar longitudinally movable, a seg-

mental rack carried by said bar, a lever controlled pinion, said pinion being adapted to engage the rack and move the bar forwardly a limited degree when said pinion 15 is rotated in one direction by said lever, and an elongated tooth carried by the pinion adapted to enter a recess in the bar and be utilized for giving the crusher bar its final forward movement.

JAMES EDWARD DOWD.
